UNITED STATES PATENT OFFICE

2,496,833

BEDCLOTHES CLAMP

Bronislaw Wandel, Boston, Mass.

Application December 19, 1945, Serial No. 635,900

1 Claim. (Cl. 24—72.5)

1

My invention relates to clamp attachments for cribs, bedsteads and the like, such as are provided and used to hold in place the sheets, blankets and other bedclothes, thereby to prevent displacement thereof through movements of the occupant.

The invention has for its object to provide, as a new article of manufacture, an efficient, attractive and inexpensive attachment of the character described which, in the preferred embodiment thereof, may consist in most part of a single piece of round wire or bar stock bent to shape so as to provide the same with a cantilever arm having means at one end thereof for clutching a slat or post of the bed or crib so that the free end of said arm is maintained in holding engagement with the bedclothes, the intermediate portion of said arm being bent laterally and upwardly to provide the same with a handle by means of which the device can be conveniently manipulated when applying the same to, or removing it from, a crib or bedstead.

Other features of the invention are hereinafter pointed out.

In the accompanying drawings:

Figure 1 is a top plan view of a bedclothes clamp constructed in accordance with this invention.

Figure 2 is a side elevation partly in section of the clamp showing the same applied to a vertical slat or post of a crib.

The illustrated embodiment of the invention is made from a round rod of either a synthetic thermoplastic resin or of steel, one-quarter of an inch in diameter and twenty-two inches long. When made of steel the device may be plated with chromium, cadmium or nickel and buffed to give to it an attractive appearance. When made from synthetic resin no plating or polishing is necessary, and moreover such material may be procured either water-clear or colored which is advantageous when it is desired to have the color of the device harmonize with the color of the bedclothes.

The rod referred to is bent to provide an approximately straight cantilever arm 10 whereof one end is formed with two spaced-apart opposed crotches 11 and 12 disposed one above the other which embrace the slat or post 13 of the crib or bedstead from opposite sides thereof so as to firmly clutch the post or slat when an upward pressure is imposed upon the outer free end of the cantilever arm 10, the arms 14 and 15 of the crotches that are disposed upon one side of the slat or post 13 being connected by an S-shaped portion 16 of the rod.

The intermediate portion 17 of the crotch 12 has mounted upon it a tubular sheath 18 of resilient rubber which frictionally engages the slat or post 13 and also protects the latter against injury.

2

The intermediate portion of the cantilever arm 10 is coiled into an upwardly extending loop 19 which provides a handle by means of which the device may be conveniently and expeditiously manipulated when applying it to and removing it from the slat or post 13 of the crib or bedstead.

At its free end the cantilever arm 10 is formed with a short downwardly projecting hook-like terminal portion 20 upon which is telescopically 10 and permanently fitted a cap 21 of resilient rubber which shields the bedclothes against injury and also frictionally engages the latter.

It will be understood that the bedclothes and mattress of a crib or bedstead are markedly 15 springy and therefore when the device is applied to a vertical slat or post and shoved downwardly the free end of the cantilever arm 10 will compress the same with the result that an upward pressure will be imposed upon the free end of arm 10 thereby causing crotches 11 and 12 to tightly clutch the slat or post 13 and hold the device against upward displacement thereon during use of the crib or bedstead. It is also true that the length of that portion of the bar stock 20 which constitutes the cantilever arm 10 with its loop 19 is sufficiently great to give to said arm 10 a substantial degree of springiness or lateral resiliency so that when in engagement with the bedclothes 22 it is under stress and slightly 25 flexed.

What I claim is:

A bedclothes clamp made from a single length of bar stock having one end portion formed with 35 a pair of opposed spaced-apart crotches disposed one above the other and adapted to embrace a slat or post of a crib or bedstead at opposite sides thereof, and said length of bar stock having its opposite end portion extending directly outwardly from one side of the lowermost crotch to provide a cantilever arm for engagement at its free end with the bedclothes thereby to cause said crotches to clutch said slat or post so that the clamp is held against displacement thereon, said cantilever arm having its intermediate portion 40 provided with an upstanding handle loop and its outer end portion formed with a relatively short downwardly extending portion for endwise engagement with the bedclothes.

BRONISLAW WANDEL.
